Patented May 17, 1921.

WITNESS:

W. Bell.

INVENTOR,
Homer A. Tiffatry,
BY
John Edward,
ATTORNEY.

UNITED STATES PATENT OFFICE.

HOMER A. TIFFANY, OF PATERSON, NEW JERSEY.

SPINDLE.

1,378,497.

Specification of Letters Patent. Patented May 17, 1921.

Application filed May 14, 1920. Serial No. 381,298.

To all whom it may concern:

Be it known that I, HOMER A. TIFFANY, a citizen of the United States, residing at Paterson, in the county of Passaic and State 5 of New Jersey, have invented certain new and useful Improvements in Spindles, of which the following is a specification.

The object of this invention is to provide a simple and reliable means for holding a 10 spindle against movement axially in its bearing, and more particularly to construct the said means so that the spindle may at will be removed from the bearing, avoiding the usual expedient employed in spindles 15 used for spinning and the like and consisting of a hook-shaped catch on the spindle rail or equivalent adapted to be turned or in some way moved into locking engagement with a flange on the spindle (usually 20 on its whirl), which expedient is objectionable in that the flange adds load to the spindle and the catch forms an undesirable projection on the rail or equivalent.

I have illustrated my invention by reference 25 to a spinning spindle,

Figure 1 of the accompanying drawing showing the spindle and its housing or bolster provided with the present improvement partly in elevation and partly in vertical section; and

Fig. 2 being a sectional view on line 2—2, Fig. 1.

a is the spindle and *b* its whirl, which in the present case is shown plain, to wit, without the usual flange alluded to above.

c is the housing or bolster for the spindle, the bearing for the spindle being indicated at *d* and being a step-bearing. Within the bearing the spindle is circumferentially reduced, forming an upwardly facing stop- 40 shoulder at *e*.

The housing is enlarged at *f* to form a base to rest on the spindle rail or equivalent, as the arm *g* projecting from the rail (not 45 shown), to which it is secured by the clamping action of said base and a nut *h* screwed on the reduced threaded lower end *i* of the housing; this, however, is immaterial.

The housing has adjoining the bearing an 50 interior stop-shoulder *k* arranged relatively reverse to the stop-shoulder *e*.

Between the stop-shoulders and contained in the housing is a detent-device *l*, 55 preferably of the rolling type, being here a hardened ball such as is used in ordinary ball-bearings. In the example illustrated,

the detent-device, which bears against both shoulders at once when the spindle is moved in the direction in which its stop-shoulder *e* would approach stop-shoulder *k* (*i. e.*, raised), positively blocks such movement of the spindle, the housing having means to hold the ball in this positive blocking position, thus:

A removable part of the housing is a 65 screw-plug *m* and a yielding part of such housing is a spiral spring *n* arranged inward of and seated at one end against the plug in axial alinement therewith, pressing at its other end against the ball, the spring being 70 arranged in a bore which at its outer end is closed by the plug. This bore, *o*, is formed so as to produce with the spindle an upwardly-pointing acute angle, terminating at its upper end at the bearing *d*, and its terminus forms the aforesaid stop-shoulder *k*. Said stop-shoulder, which is substantially perpendicular to the spindle in the present instance, extends outwardly from the latter 75 only so far that the adjoining part *p* of the bore becomes a seat or abutment for the detent-device which, when it abuts the stop-shoulder, is prevented by such seat from movement from the spindle in a direction substantially perpendicular thereto. In the 80 present instance, as indicated, the ball positively blocks the upward movement of the spindle as an incident, for instance, of doffing; I do not wish to be limited, however, to the blocking being positive in character. 90

In order to permit the ball to be withdrawn from the blocking position, especially where, as here assumed, it is a positively blocking relation that obtains, I provide the housing with an aperture *q* which leads 95 from the exterior thereof downwardly to a point over the ball; this aperture may be enlarged at its upper end to form an oil well, so that it serves in lubricating the spindle. When it becomes necessary to remove the 100 spindle for any purpose from its bearing the aperture serves to admit a wire or equivalent implement for applying against the ball the pressure necessary to depress it out of interposed relation to the shoulders 105 *e* and *k*.

It is preferable that the detent-device be a ball or equivalent rolling or anti-friction element so that when it acts to resist the upward movement of the spindle, as in doffing, 110 it will do so with the minimum amount of binding.

In forming the bore the terminus thereof is preferably left restricted to sufficiently less diameter than that of the ball, as indicated at r in Fig. 2, so that the ball does not 5 contact with (and thus add resistance to the rotation of) the spindle, which it actually never engages except at its shoulder e . This is accomplished through forming the bore (which in the example is cylindrical and is 10 drilled) at an incline to the bearing d , driving in the drill until it breaks through into the bore but stopping the drill before it is exposed for its full diameter at the bore.

I do not wish to be limited to any of the 15 details hereinbefore alluded to except as they are specified in the appended claims, what I claim being—

1. In combination, a spindle having a circumferential stop-shoulder, a housing structure having a bearing for the spindle and also an upwardly reaching bore terminating at said bearing and at its terminus forming a stop-shoulder relatively reverse to the first stop-shoulder, and a detent-device in 20 said bore occupying a position where it is interposed between and is adapted to bear on said shoulders, said bore near its said terminus preventing movement of said device from said position in a direction substantially perpendicular to the spindle and the housing structure having elastic means holding the detent-device in said position and also having a downwardly reaching 25 aperture leading from the exterior of the housing to the terminal portion of the bore and adapted to admit an implement for dis- 30 placing said device in the bore and from the

terminal toward the opposite end of the bore.

2. In combination, a spindle having a circumferential stop-shoulder, a housing structure having a bearing for the spindle and also a bore terminating at said bearing and at its terminus forming a stop-shoulder relatively reverse to the first stop-shoulder, 40 and a detent-device in said bore occupying a position where it is interposed between and is adapted to bear on said shoulders, said bore having its terminus formed relatively restricted and limiting the movement of 45 the detent device toward the spindle and the housing structure having means normally holding the detent-device in said position.

3. In combination, a spindle having a circumferentially reduced portion and at one side of said reduced portion a circumferential stop-shoulder, a housing structure having a bearing for the spindle and also a bore terminating at said bearing and opposite the reduced portion of the spindle and at its terminus forming a stop-shoulder relatively reverse to the first stop-shoulder, and a detent device movable in said bore to a position where it is interposed between 60 and is adapted to bear on said shoulders, said housing structure having means normally urging the detent device to said position and also having means to withhold said device from contact with said reduced portion of the spindle. 65

In testimony whereof I affix my signature.

HOMER A. TIFFANY.
